BOX-SEALING MACHINE

Michael G. Shenigo, Sandusky, Ohio, assignor, by mesne assignments, to West Virginia Pulp and Paper Company, New York, N.Y., a corporation of Delaware

Application August 9, 1957, Serial No. 677,330

16 Claims. (Cl. 53—374)

The proposed invention relates to packaging machinery and particularly to machines for packing large and heavy articles in paperboard cartons.

The advantages of replacing lumber crates and other costly and cumbersome packing containers with paperboard cartons are obvious, and during recent years there has been a trend toward use of paperboard for packing an increasing variety of products. This trend has extended to the packing of large and heavy mass produced articles, such as domestic washing machines and other large appliances and similar articles. Machines have in fact been provided which enable mass-produced heavy and bulky objects to be cheaply and efficiently packaged in paperboard cartons without lifting the object to be packed, while at the same time obtaining a trim, strong and durable final package which is as acceptable from a sales point of view as are the neat small cartons in which small appliances and other objects are conventionally packaged.

The present invention contemplates and has for its general object the provision of a machine which has all the above advantages and which at the same time is adaptable to quick changeovers to cartons of a variety of dimensions. In similar machines of the prior art, changeovers to boxes of varying dimensions required that adjustments be performed by skilled men and such adjustments required shutting down the production line for 20 or 30 minutes or more. The present invention enables the changeover to be made in one minute or less.

The ready adjustability provided by the present invention accounts for adjustment of the elements for infolding carton flaps, the elements for gluing and sealing the flaps, the elements for centering the box laterally of the machine and guiding it longitudinally through the machine, and the elements for squaring the machine. In short, all the multiple complex operations to be performed in packaging the large and heavy mass-produced articles are suitably adjusted automatically and simultaneously according to the invention.

The invention contemplates the provision of a longitudinally extending fixed frame and a longitudinally extending hanging frame depending from the fixed frame and in turn supporting a longitudinally extending pair of laterally shifting guide rails. These several main structural elements are associated with the other machine elements in a manner to be more particularly described below.

The above advantages of the invention and other objects thereof will become apparent from the following description of one example of the invention. This example illustrates presently preferred means and apparatus and will enable the art to readily practice the invention for purposes of evaluation and trial, either by duplication of the illustrated means and apparatus or models thereof, or by alteration of specific details thereof to provide alternative means embodying the principles and teaching of the invention.

In the drawings:

2

Figure 1 is a plan view of a packaging machine embodying the invention, with certain parts removed to more clearly illustrate the invention, particularly at the sealing and gluing stations.

5 Figure 2 is an elevation of the machine shown in Figure 1.

Figure 3 is a sketch of the type of standard paperboard carton which may be employed in the practice of the invention.

10 Figure 4 is a view on an enlarged scale taken on line 4—4 in Figure 2.

Figure 5 is an elevational view on an enlarged scale of the gluing station of the machine shown in Figure 1.

Figure 6 is a view taken on line 6—6 in Figure 5.

15 Figure 7 is a fragmentary view on a further enlarged scale taken on line 7—7 in Figure 5.

Figure 8 is a view on the same scale as Figure 7 and taken from line 8—8 in Figure 6.

20 Figure 9 is a somewhat schematic view on a reduced scale taken from line 9—9 in Figure 6 and illustrating part of the flexible drive linkage for a certain mechanism employed in the invention.

Figure 10 is an elevation on an enlarged scale of the apparatus in the vicinity of the sealing stations of the 25 machine shown in Figure 1.

Figure 11 is a plan view of the apparatus seen in Figure 10, certain uppermost elements being cut away or eliminated for purposes of clarity.

30 Figure 12 is a view of a portion of the apparatus seen in Figure 11.

Figure 13 is a cross section taken on line 13—13 of Figure 2.

Figure 14 is an elevation of the apparatus in the vicinity of the squaring station of the machine shown in Figure 1.

Figure 15 is a view taken on line 15—15 in Figure 14.

Figure 16 is a view taken on line 16—16 in Figure 14.

Figure 17 is a view taken on line 17—17 in Figure 16.

Figure 18 is a view similar to the left and vertically central portion of Figure 15 showing an alternative form of certain portions of the apparatus.

Figure 19 is a view similar to the portion of Figure 14 which is slightly above and to the left of center showing an alternative form of certain portions of the apparatus.

45 Figure 20 is a perspective view of the apparatus shown in the previous drawings, many stationary portions of the apparatus being eliminated or being shown in phantom for the purpose of bringing out certain features of the invention.

50 In order to facilitate and condense description of the invention, the following description of the drawings will specify reference numerals of the various parts and, in parentheses, will specify the number of the figure or figures of the drawings in which such reference numerals may be found. For example, "cylinders 49, 50(4)" signifies that the particular parts referred to are given the reference numerals 49 and 50 and are to be conveniently found in Figure 4.

55 Types of paperboard cartons or containers with which the invention is particularly adapted to be utilized are conventional rectangular cartons which are most economically shipped folded flat, with their end flaps folded outwardly in the same planes as the sides of the carton. When such a carton is unfolded or expanded by moving opposing pairs of its sides away from each other, the end flaps most naturally remain in erect or longitudinally extending position. Such a carton 10(2—6, 13—16) is shown in the drawings. The illustrated carton has a forward side 11, sideward lower flaps 12 and 13, a forward lower flap 14 and rearward lower flap 15, sideward upper flaps 16 and 17, a forward upper flap 18 and a rearward upper flap 19. The conformation which such a carton will assume when it is unfolded is illustrated in Figure 3.

Objects to be packaged through use of the invention may comprise various bulky shapes. By way of example, the packaging of washing machines having a generally rectangular shape is illustrated. These heavy objects 20(2) are most preferably mounted on pallets in order to support and distribute their substantial weight. In connection with the present invention, there may be employed relatively thin inexpensive paperboard pallets 21(2, 6).

The illustrated example of the invention comprises a 10 long conveyor generally extending in the direction indicated by the arrow 25(1). The conveyor comprises numerous rollers 26 extending transversely of the path on which objects are to be translated along the conveyor. The conveyor also comprises several endless 15 belts 27—31 which either contact the bottom of certain of the rollers 26 to actuate them or are supported thereon in a manner which will be apparent from the several drawings and which will be well known to those familiar with materials handling and packaging.

As indicated in Figure 1, the conveyor 25 leads successively pass through a carton-loading station A, a gluing station B, first and second sealing stations C and D, and a squaring station E.

Carton-loading station

At the carton-loading station A, there is provided a drop-away conveyor portion which comprises conveyor segments 35 and 36(1). These conveyor segments may consist of four short rollers 26, supported in unitary side frames mounted respectively on the shafts 37 and 38. The shafts 37 and 38 are oscillated by the actuating cylinders 39 and 40 to which they are coupled by suitable crank linkages.

At either side of the loading station A, there is provided one of a pair of oppositely disposed horizontal side plates 43, 44(1, 4). Fixed to the side plates are bushing blocks 45 which slide on fixed guide rods 46. On the bushing blocks 45 are provided bosses 47 which receive yokes 48. The yokes are powered for intermittent oscillation by the actuating cylinders 49 and 50, acting through a suitable crank linkage in a manner which will be shown from the drawings. In the illustrated machine, the arrangement of the parts is such that the side plates 43 and 44 are withdrawn entirely out from under the path of passing objects when they are in their withdrawn position and extend substantially transversely across the bottom of the path when they are in their extended position. The conveyor segments 35 and 36 are substantially on a level with the remainder of the conveyor 25 when they are in their raised position.

A motor 52(1) powers the drive roll for the belt 27.

Gluing station

At the gluing station B, there is provided a stand 60(2, 5, 6) from which extend fixed horizontal frame members 65 and 62(2, 5, 6). At points remote from the stand 60, the frame members 65 and 62 may be supported by arbors 64. In each side of the stand 60 there is provided a slot 66(2, 5, 7). In each slot 66 there is slidably mounted a pillow assembly 70(2, 6, 7). Rotatably mounted on suitable bushings in each pillow assembly and extending therebetween and therethrough is a shaft 67 to which are keyed a pair of upper glue rollers 68, each of which has associated with it a glue pan 69. Extending downwardly from the top of the gluing station are chain hangers 71 and 72. In a manner most clearly seen in Figure 6, the chain hangers 71 support vertically floating horizontal frame members 61 through straps or rods 71B(6) which are spaced by a cross-arm 71A(6). The members 61 extend from the stand 60 in generally parallel relation to the frame members 65 and 62. The chain hangers 72 support the pillow assembly 70 in a manner most clearly shown in Figure 7.

An additional transverse bar 85(6) extends between the pillow assembly 70. Hooked straps 86(5, 6) depend from this bar 85 and support the upper glue pan 69. The chain hangers 71 and 72 are engaged on take-up sprockets keyed to a shaft 74. The shaft 74 is journaled on the stand 60. The shaft 74 may be actuated by a motor and speed reducer 75 acting through an endless chain linkage 76. The shaft 74 is never rotated more than a few turns. Additional sprockets 77 are fixed to the shaft 74 and engage long chains 78 which extend generally parallel to and between the fixed horizontal frame members 65. Extending as cantilevers inwardly from each pillow assembly 70 are pairs of upper guide rolls 80 which are preferably positioned with regard to the upper glue rolls 68, as indicated in Figure 5. Journaled on the stand 60 is a lower shaft 82 on which are mounted lower glue rolls 83. Associated with each of the lower glue rolls is a lower glue pan 84. Glue is fed into the upper glue pan by feed lines 87(6). 10 The glue is emptied from the upper glue pan through overflow lines 88. The overflow lines 88 lead directly to the lower glue pans 84. The lower glue pans are emptied through return lines 89(5, 6) which lead to a suitable reservoir (not shown). Glue is fed by this reservoir through the feed lines 87 by suitable pumping means (not shown). The glue is continuously circulated through the feed lines 87, the pans 69 and 84, and the return lines 89. Mounted on the stand 60 are pairs of lower guide rolls 92(5, 6) which are associated with the lower glue rolls 83 in a manner similar to the relationship of the upper glue rolls and guide rolls.

At the end of the shaft 82 on the exterior of the stand 60 is keyed a sprocket 93(6, 9). This sprocket is driven through a chain 97(6, 9) by a motor 95. The motor 95 drivingly engages the chain 97 through a jack shaft 95B(1, 9). The motor is coupled to the jack shaft 95B through an endless chain drive 95A(1). The jack shaft is coupled to the chain 97 between suitable sprockets as seen in Figure 9. The jack shaft also is coupled by an endless chain linkage to an additional shaft 95C(1, 2, 5) which powers the belts 28 and 29. Another sprocket 101(9) is keyed to the shaft 67 and engages the chain 97 in the manner shown in Figure 9. Appropriate fixed idler sprockets 98 are provided. It will be clear that the power drive for the shaft 67 is thus maintained, despite raising and lowering of the pillow assembly 70, any slight change in the amount of chain being taken up between the centers of 95B and the uppermost idler 98 being less than that play which the interengaged chain 97 and cooperating sprockets can accommodate.

At the ends of the horizontal frame members 61 are fixed two upstanding frame arms 105(2, 5). A preferably circular paddle or ring 105 is mounted on a paddle arm 115 pivoted between the arms 106. The linkage is adapted to be actuated as indicated in Figure 5 by a pneumatic cylinder linkage 107. A pair of plowing members 115A(5) extend upwardly from the ends of the horizontal frame members 61. A standard solenoid operated pneumatic control valve (not shown) which controls the pneumatic cylinder linkage 107 is itself governed by a carton-actuated microswitch 110(5) appropriately located. The relation of the parts is such that when a loaded carton 10 contacts the microswitch 108 as the carton reaches the gluing station B, the paddle 105 will be caused to swing downwardly and forces the rearmost upper flap 19 forwardly with a swiping motion and will position the flap 19 in such a way that it will be finally inwardly plowed by the plowing members 115A.

Sealing stations

Transversely extending rolls 116 are supported between the horizontal frame members 61 through the gluing station B and on the output side of the gluing station. The rolls 116 and the rolls 26 are staggered at

the sealing stations C and D, as indicated in Figure 11. That is, the rolls are foreshortened so as to extend only over the left-hand side of the conveyor (as viewed in Figure 13) at the station C and only over the right-hand side of the conveyor at station D.

The vertically floating horizontal frame members 61 are provided with extensions which may be integral therewith or which may comprise separate frame members 170(2, 10, 11, 13-15). Supported between the members 61 and/or the members 170 and bodily movable vertically therewith are a pair of upper striking members 122 and 124. A pair of lower striking members 123 and 125 are supported on the lower fixed frame member 62. Each of the striking members 122-125 comprises an arm 128 radially extending from a bell crank linkage 120, which is actuated by a pneumatic cylinder 121. Each of the striking members 122-125 also comprise a canted member 129 disposed with relation to its associated radial arm in the manner shown in the drawings. The actuating cylinders of the pneumatic cylinder linkages 107 are controlled by solenoid-operated valves (not shown) which, in turn, are controlled by the micro-switches 132 and 133(11, 13). Within the gaps formed by the staggering of the conveyor 25 at the stations C and D are located support bars 134 and 134A(11). These members are at the level of the conveyor 25 and serve to prevent containers at the stations C and D from tilting inwardly.

There are preferably provided, at least for the upper sideward flaps of passing cartons, suitable plows 135 and 136 positioned as shown in the drawings to guide the flaps from a laterally outwardly folded position to an upward position where they are ready to be most effectively engaged by the striking members 122 and 124. Similar plows may be provided for the lower sideward flaps of passing cartons but usually such flaps will normally drop to a pendant position without plowing.

The upper reach of the belt 28 terminates at the point 138(1), the upper reach of the belt 29 terminates at the point 139(1, 10), the upper reach of the belt 30 starts at the point 140(1, 10), and the upper reach of the belt 31 starts at the point 141(1, 10). It is at corresponding points along the length of the conveyor 25 that the rollers 26 and the upper rollers 116 terminate over half the extent of the conveyor width.

Squaring station

Supported between the frame members 170 are a series of transverse rolls 171(1, 2, 10, 11, 13) which depend from short straps 172(10). Adjacent the squaring station E, inwardly of one pair of arbors 64, are provided short supporting beams 173(14, 15) below each upper one of which and above each lower one of which is mounted a pneumatic cylinder linkage, generally indicated at 174, and comprising a pneumatic cylinder 175(14-16), an actuating rod 176(16) fixed to a guide yoke including the face plate 177, and integral guide rods 178. Spring-loaded bolts 181 hold squaring bars or pressers 179 against the plate 177 but allow limited canting or tilting movement thereof to lessen impact and distortion upon contact of the bars 179 with the side of a carton to be straightened. Such limited movement is illustrated in phantom in Figure 16. The actuating cylinders 175 are controlled by solenoid-actuated valves (not shown) which are, in turn, controlled by the micro-switch 180(14) mounted adjacent the conveyor immediately ahead of the squaring bars or pressers 179.

The belts 30 and 31, which extend away from the sealing station, are powered by a motor 148(1, 11) through a chain drive which is coupled to the drive roll for these belts, as clearly shown in Figure 11.

Longitudinally extending size adjustment linkage

Keyed to the shaft 74 are a pair of sprockets 145(6) on which, engaged in take-up and unwind relationship,

are a pair of long chains 146(5, 10, 11, 14) each of which is divided along its length by several coupling bars 147(10) each of which is connected to a shorter hanging chain link 149. The hanging chain links 149 are fixed to the vertically floating horizontal frame members 61 or 170, as shown in the drawings.

Mounted on a supporting beam structure 151(10-12), which straddles the longitudinally extending members 170, is a crank linkage comprising the crank shafts 152 and 153 which are joined by a transverse link 154 and each of which has formed integrally therewith a crank arm 155. The outer end of each crank arm 155 is pivotally fixed in supporting relationship to one of a pair of transversely and vertically floating frame members or guide rails 63. The crank shaft 152 is powered by a motor 156 acting through a speed reducer and endless chain linkage 157(10, 11). The members 63 at their opposite extremity are pivotally mounted in supported relationship on the end of crank arms 158(6). 20 Each of the crank arms 158 is pivotally mounted in supported relationship at its inner end on a cantilever bolt extension 159. The cantilever bolts, which form part of the cantilever bolt extensions 159, are fixed to the pillow assemblies 70 and extend through the slots 66. 25 In the particular apparatus illustrated, tilting of the trailing ends of the upper members 61 at the trailing end of the second sealing station D is avoided by providing an auxiliary hanging chain 149A(20), which is taken up by a sprocket 142(11). The sprocket 142 is linked 30 by a sleeve 143 for rotation with a sprocket 144(12) which engages one of the hanging chains 149.

Operation with packages of a given size

Objects to be packaged approach on their pallets from the left end of the apparatus as viewed in Figures 1 and 2. Additional drive belts may be provided for this feed, or the feed may be by gravity, a slight slope being provided at the input portion of the conveyor 25, or the feed may simply be manual to allow the backing up of any random number of objects being continuously supplied from a production line. As an object 20, on its pallet, enters the loading station A, the conveyor segments 35 and 36 are in their raised position. The side plates 43 and 44 are extended. After the object is positioned approximately as indicated in Figure 5, the operator grasps the opposite corner of a carton or container 10 and unfolds the container to the conformation shown in Figure 3 and places the container over the object 20. As the operator places the carton on the object, he actuates a manual control which preferably may be any suitable spring-return pneumatic control (not shown) which causes the cylinders 39 and 40 to contract, in turn causing the conveyor segments 35 and 36 to drop. The flaps 14 and 15 are disposed downwardly in pendant position below the level of the conveyor 25, as shown in Figure 6, while the flaps 12 and 13 are folded outwardly by contact with the plates 43 and 44. At this stage, the full weight of the object is borne by the plates 43 and 44. The operator now releases the control to 60 reverse the cylinders 39 and 40 and return the conveyor segments 35 and 36 to raised position. As the conveyor segments 35 and 36 move to their raised position, they force upwardly with them the flaps 14 and 15 and cause these flaps to be folded into closed position against the undersides of the side plates 43 and 44. The operator then actuates a second spring-return control (not shown) to energize the actuating cylinders 49 and 50, causing the plates 43 and 44 to be withdrawn out from under the path of the object 20. When the plates 43 and 44 70 are withdrawn, the flaps 12 and 13 are fully cleared, and the object 20, together with its container 10, is free to pass along the remainder of the conveyor 25. As the object 20 and container 10 leave the loading station, the second control is released by the operator, causing the plates 43 and 44 to again extend. The loading sta-

tion A is then ready to receive a succeeding object 20.

In the particular apparatus illustrated, the operator simply pushes the loaded carton 10 off the loading station A, whereupon it contacts the belt 27 and is carried slowly along the conveyor 25 from the station A to the station B. During this part of travel, or prior thereto while the carton is still on the loading station A, there may be placed in the top of the container padding and reinforcing means and various accessories and literature to accompany the object 20. This is easily accomplished, since the flaps 17-19 are all fully open. As the container 10 approaches the gluing station B, the upper foremost flap 18 is plowed inwardly by the plows 115A. The carton 10 contacts the microswitch 108, actuating the pneumatic cylinder linkage 107 and causing depression of the paddle 105. The paddle 105 swipes forwardly in sliding contact with the outside of the upper rear-most flap 19, shifting this flap to an almost closed position which is maintained until the flap 19 contacts the plows 115A to be fully closed thereby.

Side plows 108(2) are provided to guide the flaps 16 and 17 to assure that the flaps 16 and 17 enter the gluing station in a laterally outwardly extending position. The flaps 12 and 13 also enter in this position due to their engagement with the top sides of the conveyor 25. The flaps 16 and 17 are glued by the upper glue rolls 68, and the flaps 12 and 13 are glued by the lower glue rolls 83. Each glue roll and its associated guide rolls 80 or 92 are preferably positioned so that a common plane is tangent to each roll or so that the glue roll extends slightly within the plane which is tangent to the pair of associated guide rolls. As each flap passes beyond the leading guide roll and engages the glue roll, it is therefore very slightly bent, and, as it continues and engages the trailing guide roll, it is again very slightly bent in the opposite direction. This provides a highly satisfactory glue-applying action and eliminates any tendency of the flaps to be deformed or sprung or the glue thereon to be splattered by engagement and disengagement with spring-loaded mandrels or similar spring-loaded devices conventionally used to force flaps to be pressed firmly against glue-applying rolls.

As the carton 10, with its sideward flaps now glued, leaves the station B and approaches the station C, it is positioned between the points 138 and 140. At this point, the upper flap 17 is plowed upwardly by the plow 136, and the carton 10 then contacts the microswitch 133, causing the cylinder 130 to be energized and causing the striking members 124 and 125 to swing inwardly. The canted member 129 associated with the striking members 124 and 125 strikes the flaps 17 and 13 with a follow-up action which causes full and complete closure of these flaps. The flap 13 closes "over" the member 134. As the carton 10 continues to station D, this flap-closing action is duplicated for the flaps 12 and 16. The flap 16 is plowed upwardly by a plow 135. The carton contacts the microswitch 132 causing actuation of the striking members 122 and 123 and accomplishing inward folding of the flaps 16 and 12. The flap 12 closes "over" the member 134A. As the carton leaves each station C or D, the members 134 or 134A are left behind and pass out from "under" the flaps 13 and 12 across the rearmost sides thereof.

As the carton leaves the sealing stations C and D, it ends contact with the microswitches 133 and 132, respectively, causing the various striking members 122-125 to return to their normal position for the reception of a succeeding carton. As the carton 10 enters the squaring station, it strikes the microswitch 180, causing the squaring bars 179 to be shifted outwardly, releasing the carton preceding the carton 10. Driven by the belts 30 and 31, the carton 10 enters between the squaring bars 179 and forces the preceding carton out from therebetween. As the carton 10 fully enters between the

sealing bars 179, contact with the microswitch 180 ends, and the sealing bars shift toward closed position. The carton 10 is therefore held in firm and square position by the bars 179 and the weighted rolls 171 until such time as it is displaced by a succeeding loaded carton. The glue is preferably chosen so that its setting time is such that it will still be somewhat fluid after the interval of passage from the station B to the station E but will set by the time the carton is displaced from the squaring station E.

The structure as described above is versatile and capable of being quickly adjusted to accommodate cartons which vary widely in their width and height. Furthermore, since the guide rails 63 and the squaring bars 179 adjust upwardly and downwardly automatically according to the particular height adjustment which is chosen, these guide rails and squaring bars are automatically positioned correctly in guiding and retaining or squaring engagement with cartons of all sizes. When it is desired to changeover from one size to another, it is only necessary to actuate the motor 75 sufficiently to effect the desired height adjustment and to actuate the motor 156 sufficiently to effect the desired width adjustment. When the height adjustment is made the rolls 116 and 171 are raised or lowered in relation to the rolls 26. At the same time, the guide rails 61 are correspondingly raised or lowered, being carried bodily by the linkages 152-155 and at their leading ends by the cantilever bolts 159 and crank arms 158. The upper striking members 122 and 124 at the sealing stations, together with their associated actuating linkages and cylinders 121, also move up and down with the frame members 61 or 170 when the height adjustment is made. So also do the upper glue rolls 80 and associated elements which move with the vertically shifting pillow assemblies 70. The upper squaring bars or pressers 179 and associated linkages including the actuating cylinders 175 therefor are also carried bodily with the vertically adjustable longitudinal frame members. The frame members 61 and 170 are suspended by the hanging chain portions 149 associated with the long chains 146 and coupling bars 147. The leading ends of the frame members 61 are raised and lowered by raising and lowering of the straps 71B which are supported by the chain hangers 71. The chain hangers 71, 72 and the long chains 146 are taken up on the shaft 74 by means of suitable sprockets, as indicated in the drawings.

Linkage for delay of vertical adjustment of pressers

It should be noted that it only requires several seconds for any given carton to proceed through the gluing station and the sealing stations C and D to the squaring station E. Accordingly, but for the engagement of the squaring bars or pressers 179 with passing cartons, the machine is free to be vertically adjusted for another height (within the vertical range or capacity afforded by the pivoted suspension of the rolls 171) after a very short interval of time following the reception of a machine of a given height. This short time interval is enough to allow repeated changeover between packages varying in height by several inches. Where two models are being made on a single production line, it is not uncommon to deliver to the packaging operation one model and then another in constant alternation, with the two models differing in height by several inches. In order to render the machine capable of accepting such alternating cartons without having to clear the machine, there may be provided a resilient linkage means for allowing the upper set of oppositely disposed pressers 179 to be restrained from following up and down movement of the frame members 63 and 170 until they are disengaged from passing cartons. Such a linkage is shown in Figures 18 and 19 which illustrate modifications in certain portions of the structure shown in Figures 15 and 14, respectively. Instead of being fixed to short support beams or spacer

beams 173, as shown in Figures 14 and 15, the cylinders 175 and their associated linkages including the pressers 179, guide rods 178 and other associated elements, are carried bodily by a pair of pins 185 received in bosses 186 fixed in the adjacent cross beam between the members 170. Springs 187 below the bosses urge each presser assembly downwardly, and spring 188 above the bosses act against washers 189 fixed to each pin 185 to urge each presser assembly upwardly, the springs 187 and 188 coacting to maintain the upper presser assemblies in vertically centered relationship with respect to the frame assembly with which they move. When a height adjustment of several inches is to be made, it is only necessary to allow the machine to clear through to the squaring station. When the clearing carton arrives at the squaring station to be engaged by the pressers 179, the height adjustment can be made. The springs 187 and 188 accommodate the vertical movement even though the pressers 179 are engaged with the just-cleared carton. When this carton is subsequently released, the upper pressers 179 will automatically spring to a centered position corresponding to the newly chosen vertical adjustment of the machine as a whole. The pivoted mounting of the rolls 171 allows such vertical adjustment to be made even though the machine is filled with cartons on the output side of the squaring station.

For fairly extreme size adjustments, the entire machine should be cleared before effecting the changeover.

It will be apparent that many variations in the many details of the illustrated apparatus will be possible. The invention is not limited to these details, but its scope is to be determined by the following claims.

What is claimed is:

1. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton, and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to

ward flap associated with each passing carton, said first and second upper striking means being carried bodily by said generally horizontal frame and being bodily movable therewith, means to actuate each of said striking means in response to positioning of approaching cartons, rotatable rolls hung transversely across said conveyor means between said second sealing station and said squaring station, hanging means for said rolls comprising journal means yielding upwardly translatable against the weight of said rolls through a vertical range of travel, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily by said generally horizontal frame and being bodily movable therewith, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

2. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to

positioning of approaching cartons, rotatable rolls hung transversely across said conveyor means between said second sealing station and said squaring station, hanging means for said rolls comprising journal means yieldingly upwardly translatable against the weight of said rolls through a vertical range of travel, oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

3. In a machine for packaging large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, rotatable rolls hung transversely across said conveyor means between said second sealing station and said squaring station, hanging means for said rolls comprising journal means yieldingly upwardly translatable against the weight of said rolls through a vertical range of travel, upper and lower oppositely disposed sets of pressers at said squaring station on opposite sides of said conveyor means, means for moving said

said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily on said generally horizontal frame by resilient linkage means for allowing said upper set of oppositely disposed pressers to be restrained from following up and down movement of said generally horizontal frame until the pressers are disengaged from pressing engagement with a passing object, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

4. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, rotatable rolls hung transversely across said conveyor means between said second sealing station and said squaring station, hanging means for said rolls comprising journal means yieldingly upwardly translatable against the weight of said rolls through a vertical range of travel, oppositely disposed pressers at said squaring station on opposite sides of said conveyor means, means for moving said

oppositely disposed pressers apart as each successive carton approaches said squaring station and for moving said oppositely disposed pressers toward each other as each successive carton completely enters said squaring station, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

5. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of upper and lower sideward flaps of each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily on said generally horizontal frame by resilient linkage means for allowing said upper set of oppositely disposed pressers to be restrained from following up and down movement of said generally horizontal frame until the pressers are disengaged from pressing engagement with a passing object, oppositely disposed guide rail means extending longitudinally along said conveyor means on either side thereof from said gluing station to said squaring station, said oppositely disposed guide rail means being carried bodily by said generally horizontal frame and being bodily movable up and down therewith.

6. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton,

means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily on said generally horizontal frame by resilient linkage means for allowing said upper set of oppositely disposed pressers to be restrained from following up and down movement of said generally horizontal frame until the pressers are disengaged from pressing engagement with a passing object, oppositely disposed guide rail means extending longitudinally along said conveyor means on either side thereof from said gluing station to said squaring station, said oppositely disposed guide rail means being carried bodily by said generally horizontal frame and being bodily movable up and down therewith.

7. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of upper and lower sideward flaps of each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily on said generally horizontal frame by resilient linkage means for allowing said upper set of oppositely disposed pressers to be restrained from following up and down movement of said generally horizontal frame until the pressers are disengaged from pressing engagement with a passing object, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

8. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations

and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily on said generally horizontal frame by resilient linkage means for allowing said upper set of oppositely disposed pressers to be restrained from following up and down movement of said generally horizontal frame until the pressers are disengaged from pressing engagement with a passing object, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

9. In a machine for packing large heavy objects in paperboard containers of rectangular shape and provided with four lower and four upper end flaps, conveyor means leading past a carton-loading station and then past a gluing station and sealing stations, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station and said sealing stations, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend under and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, oppositely disposed guide rail means extending longitudinally along said conveyor means on either side thereof from said gluing station to beyond both of said sealing stations, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, oppositely disposed guide rail means extending longitudinally along said conveyor means on either side thereof from said gluing station to beyond both of said sealing stations, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

10. In a machine for packing large heavy objects in paperboard containers of rectangular shape and provided with four lower and four upper end flaps, conveyor means leading past a carton-loading station and then past a gluing station and sealing stations, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station and said sealing stations, means for vertically translating said frame between first and second levels through a continuous range of preselectable heights for processing of runs of cartons of different heights, means at said gluing station for applying glue to the inner sides of upper and lower sideward flaps of each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, oppositely disposed guide rail means extending longitudinally along said conveyor means on either side thereof from said gluing station to beyond both of said sealing stations, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

11. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rear-

most lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily by said generally horizontal frame and being bodily movable therewith, oppositely disposed guide rail means extending longitudinally along said conveyor means on either side thereof from said gluing station to said squaring station, said oppositely disposed guide rail means being carried bodily by said generally horizontal frame and being bodily movable up and down therewith.

12. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of upper and lower sideward flaps of each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily by said generally horizontal frame and being bodily movable therewith, oppositely disposed guide rail means extending longitudinally along said conveyor means on either side thereof from said gluing station to said squaring station, said oppositely disposed guide rail means being carried bodily by said generally horizontal frame and being bodily movable up and down therewith.

13. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects

and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily by said generally horizontal frame and being bodily movable therewith, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

14. In a machine for packing large heavy objects in paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of upper and lower sideward flaps of each passing carton, means at said sealing stations for closing said upper and lower sideward flaps of each passing carton, upper and lower oppositely disposed sets of pressers at said squaring station on opposite sides of said conveyor means, means for moving said oppositely disposed pressers apart as each successive carton approaches said squaring station and for moving said oppositely disposed pressers toward each other as each successive carton completely enters said squaring station, said upper set of oppositely disposed pressers being carried bodily by said generally horizontal frame and being bodily movable therewith, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

15. In a machine for packing large heavy objects in paperboard containers of rectangular shape and pro-

vided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of opened upper sideward flaps associated with each passing carton, said last named means being carried by said frame for vertical translation therewith, means at said gluing station for applying glue to the inner sides of opened lower sideward flaps associated with each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, means at said squaring station for firmly supporting each received carton in squared attitude during setting of applied glue, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.

16. In a machine for packing large heavy objects in

60

paperboard containers of rectangular shape and provided with four lower and four upper end flaps, conveyor means leading past a carton loading station and then past a gluing station, sealing stations and a squaring station, means at said loading station for infolding under passing objects to be packaged the foremost and rearmost lower flaps of cartons which are dropped over such objects and thereupon allowing translation of each object and its carton toward said gluing station while at all times supporting such objects from beneath, a generally horizontal frame extending over said gluing station, sealing stations and squaring station, means for vertically translating said frame between first and second levels through a continuous range of preselectable heights for processing of runs of cartons of different heights, means at said gluing station for applying glue to the inner sides of upper and lower sideward flaps of each passing carton, said sealing stations comprising a first sealing station at which said conveyor means is constructed to transversely extend under and support only one first half of each passing carton to accommodate infolding of the lower sideward flap associated with the other half of the carton, a second sealing station at which said conveyor means is constructed to transversely extend and support only the other half of each passing carton to accommodate infolding of the lower sideward flap associated with the one first half of the carton, plow means at said sealing stations for initiating inward folding of the upper and lower sideward flaps associated with each passing carton, first upper striking means and first lower striking means comprising a first pair of striking means at said first sealing station for completing inward folding of one upper and one lower sideward flap associated with each passing carton and second upper striking means and second lower striking means comprising a second pair of striking means at said second sealing station for completing inward folding of the other upper and other lower sideward flap associated with each passing carton, said first and second upper striking means being carried bodily by said generally horizontal frame and being bodily movable therewith, means to actuate each of said striking means in response to positioning of approaching cartons, means at said squaring station for firmly supporting each received carton in squared attitude during setting of applied glue, oppositely disposed guide rail means extending longitudinally along said conveyor means on either side thereof from said gluing station to said squaring station, means for moving said oppositely disposed guide rail means toward and away from each other through a continuous range of preselectable spacings for processing of runs of cartons of different widths, said oppositely disposed guide rail means being carried bodily by said generally horizontal frame and being bodily movable up and down therewith.
